UNITED STATES PATENT OFFICE.

WILLIAM VESELY, OF NEW YORK, N. Y.

DESIGN FOR A COMBINED LAMP, SMOKING STAND, AND LOUD SPEAKER.

Application filed June 27, 1925. Serial No. 13,933. Term of patent 3½ years.

To all whom it may concern:

Be it known that I, WILLIAM VESELY, a citizen of the United States, residing in the city, county, and State of New York, have invented a new, original, and ornamental Design for a Combined Lamp, Smoking Stand, and Loud Speaker, of which the following is a specification, reference being had to the accompanying drawing, forming a part thereof.

I claim:

The ornamental design for a combined lamp, smoking stand, and loud speaker, substantially as shown.

WILLIAM VESELY.
